(57) **CLAIM**

An ornamental design for a soft hand restraint device for transporting prisoners, as shown and described.

DESCRIPTION

FIG. 1 is a front perspective view showing the soft hand restraint device for transporting prisoners showing the handcuff retaining strap and wrist restraints in the closed position; and,

FIG. 2 is a front perspective view showing the design of another embodiment of the soft hand restraint device for transporting prisoners having a seat belt restraint slot that incorporates the handcuff retaining strap located in the proximity of the top edge, showing the wrist restraints and the handcuff retaining strap in the closed position, beyond this aspect alone, all other elements and aspects of the design being substantially similar.
